US0D1074002S

(12) **United States Design Patent** (10) **Patent No.:** **US D1,074,002 S**
(45) **Date of Patent:** **** May 6, 2025**

(54) **HEADLIGHT**

(71) Applicant: **VOLVO CAR CORPORATION**, Gothenburg (SE)

(72) Inventor: **Sebastiano Ciarcia**, Gothenburg (SE)

(73) Assignee: **Volvo Car Corporation**, Gothenburg (SE)

(**) Term: **15 Years**

(21) Appl. No.: **29/891,218**

(22) Filed: **May 3, 2023**

(30) **Foreign Application Priority Data**

Nov. 3, 2022 (EM) 015002205-0001

(51) **LOC (15) Cl.** **26-06**

(52) **U.S. Cl.**
USPC **D26/28**

(58) **Field of Classification Search**
USPC D26/24, 28-36, 138, 139
CPC F21S 41/10; F21S 41/141; F21S 41/18;

(57) **CLAIM**

The ornamental design for a headlight as shown and described.

DESCRIPTION

FIG. 1 is a front perspective view thereof;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

Portions of the article shown in broken lines form no part of the claimed design. Portions of the article shown in de-emphasized tones within broken line boundaries are not part of the claimed design.

1 Claim, 8 Drawing Sheets
